CLAIM

The ornamental design for a base for a dispensing container, substantially as shown and described.

DESCRIPTION

FIG. 1 is a top plan view of a base for dispensing container showing our new design;

FIG. 2 is a front elevational view thereof, the rear view being a mirror image thereof;

FIG. 3 is a right side elevational view thereof, the left side being a mirror image thereof; and

FIG. 4 is a bottom plan view thereof.

FIG. 1

FIG. 2

FIG. 3

FIG. 4
